UNITED STATES PATENT OFFICE.

WILLIAM R. WILLIAMS, OF OWENSBORO, KENTUCKY, ASSIGNOR TO OWENSBORO DITCHER AND GRADER CO., OF OWENSBORO, KENTUCKY, A CORPORATION OF KENTUCKY.

ROAD-GRADING MACHINE.

1,185,358.

Specification of Letters Patent.

Patented May 30, 1916.

Application filed September 16, 1915. Serial No. 50,992.

To all whom it may concern:

Be it known that I, WILLIAM R. WILLIAMS, a citizen of the United States, residing at Owensboro, in the county of Daviess, 5 State of Kentucky, have invented a new and useful Road-Grading Machine; and I do hereby declare the following to be a full, clear, and exact description of the invention, such as will enable others skilled in the art 10 to which it appertains to make and use the same.

This invention relates to a new and useful road grading machine and ditcher.

An object of this invention is to improve 15 the construction of the road grading machine set forth, shown in the drawings, and claimed in the application of W. R. Williams, Serial No. 4,207, filed January 25, 1915, and allowed July 20, 1915, by providing improved means for adjusting the cutting blade, in order to increase or decrease 20 the cutting action of the blade.

A further object of the invention is the provision of a pair of beams angular in 25 cross section, to which the cutting blade is adjustably connected.

In practical fields the details of construction may necessitate alterations, falling within the scope of what is claimed.

30 The invention comprises further features and combination of parts, as hereinafter set forth, shown in the drawings and claimed.

In the drawings: Figure 1 is a plan view of the improved road grading and ditching, 35 machine constructed in accordance with the invention. Fig. 2 is a view in side elevation, showing parts in dotted lines. Fig. 3 is a view in elevation of the angle beams, which support the cutting blades looking in the 40 direction of the arrow *a* in Fig. 1, illustrating the means carried by the angle beams for raising the same and the cutting blade. Fig. 4 is a detail perspective view of the cutting blade. Fig. 5 is a sectional view on line 5—5 45 of Fig. 1. Fig. 6 is a sectional view on line 6—6 of Fig. 1. Fig. 7 is a sectional view on line 7—7 of Fig. 5. Fig. 8 is a detail view more clearly showing the parts 68 and 69 swivelly connected at 70, so as to be held ad- 50 justed by the set screw 71.

Referring more especially to the drawing, 1 designates the runner, which is constructed of two beams 2 and 3 angular in cross section, and arranged in parallelism one above the other. Arranged between the lateral flanges of the beams 2 and 3 is a laterally extending platform 4, there being angular straps 5 secured at 6 to the upper and lower surfaces of the platform, and at 7 to the beams 2 and 3, thereby securing the platform to the beams, and at the same time holding the beams relative to each other. Secured between the rear parts of the beams 2 and 3 as at 8 is a plate 9 having a laterally extending threaded projection 10, shown in 60 dotted lines in Fig. 1. Journalized upon the projection 10 is a supporting and cutting disk 11, which is held upon the projection by the nut 12. A metal strap or plate 13, which is bent upon itself, as shown at 14, has its 65 opposite sides 15 secured at 16 to the forward adjacent ends of the beams 2 and 3, thereby holding the forward ends of the beams firm and rigid. Arranged laterally and extending rearwardly is a holder for 70 a cutting blade comprising a pair of beams 17 and 18, which have their forward ends held rigid relative to each other by the opposite sides 19 of the plate 20, which opposite sides are secured at 21 to the beams 17 and 18. 75 The plate 20 is bent upon itself as shown at 22, in order to provide the opposite sides 19. Where the plate 20 is bent upon itself, it is restricted or contracted, in order to fit the opening 23 of the plate 13, there being a 80 pivot pin 24 passing vertically through the looped or folded or bent parts of said plates, in order to hingedly connect them. Also pivotally mounted upon the pivot pin 24 are the ears 25 of the bracket plate 26, and 85 pivoted swivelly at 27 to the bracket plate is a looped member 28, which may swivel upon the pivot 27, whereas the bracket plate 26 may pivot horizontally upon the pin 24. The forward end of the looped member 28 90 has a hook 29, to which a suitable equalizer or evener may be connected for pulling the apparatus. A bolt 30 extends transversely of the looped member 28, and is secured by the nuts 31 and 32, and upon one end of the 95 100

bolt, a supporting and cutting disk 33 is journaled, which disk and the disk 11 constitutes means for supporting the beams 2 and 3, as the apparatus is pulled over the road.

It will be observed that when turning, the bracket plate 26 will move horizontally on its pivot 24. Blocks 34 are arranged against the forward outer faces of the beams 17 and 18. Secured at 35 to the convexed face of the cutting blade 36 are angular shaped members 37 and 38, which are so arranged as to form channels 39. These angular shaped members are further arranged spaced apart so as to form open ended slots 40. Arranged in the channels 39 are clamping blocks 41, which are provided with studs 42 extending through the slots 40, and through the blocks 34, and also through the vertical flanges of the beams 17 and 18, and threaded upon the studs are the nuts 44, thereby securing the parts together.

It is to be observed that by loosening the nuts 44, the cutting blade 36 may be adjusted vertically, so that the depth of the cut made by the blade may be increased or decreased, and after the blade is once adjusted, the nuts 44 may be tightened, thereby not only holding the parts together, but also hold the beams 17 and 18 relative to each other. Pivoted at 45 between the lateral flanges of the beams 17 and 18 adjacent their outer ends is an elongated link or strap 46, the end 47 of which is pivoted upon a bolt 48 passing through the lateral flanges of the beams 2 and 3. By adjusting the bolt 48 through any two of the registering apertures 49 of the lateral flanges of the beams 2 and 3, the angular position of the beams 17 and 18 and the cutter, in plan view, may be increased or decreased, in accordance with the width of the cut desired to be made by the cutting blade.

Secured at 50 between the lateral flanges of the beams 17 and 18 is a lateral projection 51 of a segmental rack or quadrant 52, and secured on a threaded stud 53 (which is arranged centrally of the rack or quadrant) by means of a nut 54 is a lever 55. This lever 55 is provided with a dog 56, which is under the tension of the spring 57, and is connected in the usual manner with a hand grip 58, so that the dog may be manipulated to engage any one of the notches 59 of the rack or quadrant, to hold the lever in adjusted position. One end of the lever 55 has an angular and downwardly and rearwardly extending part 60, to which a forked member 61 is swiveled in any suitable manner as shown at 62, which forked member carries a wheel 63, designed to travel upon the ground or road as the machine or apparatus travels thereover.

It is to be observed that by raising the

lever 55 in the manner shown in dotted lines 65 in Fig. 3, the wheel 63 is thrown downwardly, thereby raising the beams 17 and 18 and the cutting blade, so that the cutting blade will pass over a stone or other obstacle or obstruction.

It is to be observed that the cutting blade 36 has upper and lower cutting edges 64 and 65, in which case the blade may be inverted, by removing the nut 44, and re-connecting the blade. However, the beams may be thrown to the left or upon the right of the beams 2 and 3, in which case the beams 2 and 3 will swivel axially, with relation to the looped member 28. When disposing the beams 17 and 18 upon the opposite sides of the beams 2 and 3, the dog 56 may engage the notches 67, when it is desired to raise the beams 17 and 18 and the cutting blade. The part of the lever 55 to which the forked member 60 is connected swivelly consists of two parts 68 and 69 swivelly connected at 70, so that the part 69 may be adjusted swivelly with relation to the part 68, and held so adjusted by the set screw 71, so that when flipping the cutting blade just the reverse to that shown in Fig. 1, the forked member will extend downwardly. In this manner the cutting blade in the beams 17 and 18 may be raised and lowered by the lever 55, whether the cutting blade is on one side of the beams 2 and 3 or the other side.

The invention having been set forth, what is claimed as new and useful is:—

1. In a road grading machine, a holder for a cutting blade comprising a pair of rearwardly and laterally extending angle beams, one flange of each beam being vertical, a cutting blade, and means to connect the cutting blade to said beams so that the cutting blade may be adjusted vertically relative to the beams, which means also permits the blade to be inverted, the blade being curved in cross section, said means consisting of blocks carried by the beams, members being secured in pairs to the convexed surface of the blade, the members of each pair being spaced apart to form slots and having their opposite portions undercut to form a channel, blocks in the channels and having threaded projections extending through the slots and the first blocks and through the vertical flanges of the beams, and means threaded on the projections to hold the parts together.

2. In a road grading machine, a supporting beam for a scraper blade consisting of two angle bars, one above the other and in parallelism and spaced from each other, one flange of each bar being vertical, a scraper blade having upper and lower cutting edges, a pair of connections to connect the blade to the bars, each of said connections consisting of a block carried by the beam, a pair of ele-

ments bolted to the rear face of the blade spaced from each other to form a slot, and having their opposed portions undercut to form a channel, a block in said channel and having threaded bolts passing through the slot and through the block and through the vertical flanges of the two bars, and provided with nuts to hold the parts together.

In testimony whereof I have signed my name to this specification in the presence of **10** two subscribing witnesses.

WILLIAM R. WILLIAMS.
